*R. Waddell,
Steam Balanced Valve.*

No 10,999.

Patented June 6, 1854.

Fig. 1

UNITED STATES PATENT OFFICE.

ROBERT WADDELL, OF ENGLAND.

BALANCING SLIDE-VALVE OF STEAM-ENGINES.

Specification of Letters Patent No. 10,999, dated June 6, 1854.

To all whom it may concern:

Be it known that I, ROBERT WADDELL, of England, have invented certain new and useful Improvements in Steam-Engines, 5 more peculiarly adapted to engines used on board ship, some of which, however, may be used with great advantage in various classes of engines.

These improvements relate first to certain 10 contrivances for freeing the various species of slide valve from the pressure of the steam; second, to a method of balancing the valve in such manner that it is neither held against the port when there is a vacuum 15 therein or driven from it when there is a pressure of steam in that end of the cylinder to which the port leads.

The nature of the first part of my invention consists in placing within a slide 20 valve a species of table or support provided with a rim or its equivalent against which the inside of the valve plays steam tight, a connection being made in some manner between the chamber thus formed by the valve, 25 the table and the rim and the interior of the steam chest.

The object herein attained is not a new one, as many plans have been contrived for 30 freeing the back of the valve from the pressure thereon, the usual method being either to pack the back of the valve to the top of the chest or vice versa, or to make the valve in two pieces one of which fits as a kind of piston within the other. My plan is, however, 35 entirely different from these, is more simple, inexpensive, and less liable to get out of order and has the further and great advantage that the valve continually by its own wear grinds the packing tight, for as 40 the valve wears away its own face, or its seats, so in my plan does it wear its own back or the rims of the table before alluded to. Moreover, by my plan a certain portion of the wear of the valve is transferred from 45 its face to its back and the same amount of friction is expended upon a larger surface. The valve as a whole therefore wears longer and is less liable to seize or abrade the faces of the seat than other equilibrium slide 50 valves.

The nature of the second part of my invention consists in abutting packing from 55 the top of the chest against the back of the valve in such manner that said packing shall isolate from the steam chest a small

portion of the back of the valve equal or nearly so in area to the steam port. This packing in connection with the back of the valve and the inner surface of the steam chest forms a little chamber which is opposite one of the ports and connected thereto by means of a pipe or its equivalent. The pressure in this little chamber will therefore be equal to the pressure in the port, so will the vacuum therein and it is clear that 60 the valve if balanced in other parts of its length will neither press against the port nor be pushed away from it.

Having thus essayed to give some idea of the nature of the parts of my invention and set forth some of their more obvious peculiarities and advantages I will proceed to describe by reference to the drawings one form of apparatus embracing them all and exhibiting them clearly.

Figure 1 of said drawings is a sectional view through the cylinder, valve chest, condenser, and air pump of a side lever engine. In said view is also shown in elevation the steam pipe and throttle valve. Fig. 2 is a perspective view of the equilibrium table. Fig. 3 is a horizontal view of the freeing valve for the condenser, Fig. 4 being a transverse section across the body of a ship, showing portions of the paddle wheels, steam pipes, throttle valve, levers, and small controlling cylinders, one of which in this instance is bolted to each side of the vessel.

The same letters refer to the same parts in all the figures.

The cylinder of the engine is shown at *a*, with ports *b* and *c*, connecting as usual with the steam chest *d*. In this chest plays a slide valve *e*. Within the valve is bolted or otherwise secured to the face of the steam chest the table *f*, which has all around it a projecting ledge, as *g*. The top of the table is solid, as shown at *h*, and its bottom *i*, is pierced with several holes or passages *j*, which lie directly over the passage for the exhaust at *k*. Steam is admitted to the steam chest through the apertures *l*, or either of them, and the exhaust is in any of the ordinary manners connected with the channel way *m* and the condenser *n*. The back of the valve is pierced with one or more passages *o*, and its inner face is ground so as to play steam tight upon the ledge *g*. Upon the back of the valve rest the packing pieces *p*, set up by screws 105

or other appropriate contrivances, and so arranged that they inclose on the back of the valves an area equal or nearly so to the ports *b* and *c*. These inclosures communicate with the ports by means of small passages, clearly shown in the drawings, while the space *q* is connected with the rest of the valve chest, or with the condenser, or is open to the air. This valve is purposely drawn 5 in a position where both ports are covered and I will now explain how it is in equilibrium.

There is steam on the upper side of the piston and the lower side with the whole interior of the valve is *in vacuo*. The steam in the chest presses equally in both directions upon the ends of the valve, and also backward and forward and sidewise upon such portions of it as overlap the ports.

10 The space *r*, is filled with steam of the same pressure as that which will fill the upper end of the cylinder, and the space *s* is *in vacuo* to the same extent as the lower end of the cylinder, while the apertures *o o* connect the two sides of the back of the valve and equalize the pressure that might act on either of them, depending upon the tension of the fluid with which *q* is filled. The grinding of the inside of the back of the 15 valve prevents any leakage past the rim or ledge *g*, and the valve is on every side perfectly balanced. It is thus balanced in every position that it can assume and needs to move it only sufficient force to overcome 20 the slight friction of the packing at *p p*. Any known species of slide may thus be balanced, all that is necessary being to change the contour of the table ledge and the packings in such manner that they may 25 perfectly adapt themselves to the form of the slide or valve proper.

In the condenser *n*, a float *r'* is attached to one end of a lever *s'*, pivoted at *t*, whose other extremity plays freely within a guide 30 *u*. To this lever is attached by means of connecting rods and bell cranks or other appropriate devices a slide or other valve *v*, which when put in motion opens and closes the injection pipe *w*, whose mouth is located 35 as usual above the showering plate *x*. This valve with all its connections lies inside the condenser, so as to obviate all necessity of stuffing boxes or similar contrivances which would be needed if the connecting rods, etc., 40 were located outside thereof.

Another valve *y*, is by means of a pin *z* connected to the lever *s'*. This latter valve slides in a seat outside the channel way and closes or opens an aperture which connects 45 said channel way with the outer air. This valve when the engine is at work and the aperture is shut by it is kept close against its seat by the pressure of the air, there being a vacuum in the channel way, and is so 50 much larger than the aperture that it can

be moved through a considerable distance before it commences to open the aperture *a'*.

The foot valve is represented at *b²*, the air pump bucket and valve at *b³*, and the delivery door at *b⁴*, a portion of the hot well 55 and air vessel being shown at *b⁵ b⁵*.

The action of this apparatus is as follows:—As water commences to accumulate in the bottom of the condenser, the float *r'*, rises and gradually closes the valve *v*, thus 60 shutting off a portion and finally the whole of the injection water, the valve *y*, rising at the same time, but not commencing to open the aperture *a'* until the valve *v* has shut off the injection. The aperture *a'* then commences to open and as soon as it does so 65 air rushes into the condenser, establishes an equilibrium between the condenser and the outer air and the water in *n*, runs out into the bottom of the ship. As the water falls 70 to its proper level, *r'* falls and closes *a'*, while it opens *u* and the parts again take the position shown in the drawings.

To the extremity of the pin *z* and outside of the channel way is attached a rod *m'* connected to a handle *n'*, by means of which the lever *s'* can be gently vibrated, so that the engineer may assure himself that all the parts are in proper order. By means of this 75 also the valve *y* can be made to operate as a shifting valve.

The opening of *a'* by means of *y* will cause a violent rush of air to the condenser, accompanied with much noise and will effectively arouse the attention of an engineer 80 who has been heedless of all other warnings as to the condition of his condenser. It is obvious also that either valve alone when attached to a float will produce a good effect, but the best result will follow when both are 85 applied substantially in the manner described.

In Fig. 4, the pistons, cylinders, steam pipes, etc., are purposely represented on a much larger scale than the vessel and the 90 paddles. A section of the vessel is represented at *v' v'*, the lower float boards and wheel arms at *p' p'* and the steam pipes at *s² s²*. Two small cylinders *c' c²* are firmly bolted to the sides of the vessel. Each of 95 these is provided with an appropriate piston and piston rod, which latter is by means of a pin connected with a slot in a lever attached to a throttle valve shown in dotted lines. Each of these levers is bent and has applied 100 to its other extremity a weight *w'*. The piston rod of *c'* has also applied to it a spring *d'* resting with one extremity against a collar *e'* attached to the piston rod and at its other against a collar *f'* attached by 105 some proper means to the vessel, but not shown in the drawings. This spring therefore tends to press the piston outward, and the weights *w' w'* have the same effect. 110 Each cylinder is freely connected with the 115

water outside of the vessel by means of apertures $g' g^2$, which can in case of accident to either cylinder or piston be closed by stop valves $h' h^2$. Each piston rod is by means 5 of appropriate connecting rods $k' k^2$ connected with the opposite ends of a small lever beam l' and both cylinders are open on their inner ends. When the vessel is on an even keel and the floats have their proper 10 dip the weights or springs, or both, are so adjusted that the pistons will take the position shown in the drawings, the pressure of the water on one side being balanced by the power of the weights or springs acting upon 15 the piston rods and the throttle valves will be wide open. As the water leaves the wheels, the pistons will move outward as the pressure of water thereon decreases, and the throttle valves will commence to close, shutting off steam and slowing down the engines. 20 The contrary effects take place as the wheels become again immersed. In double engine ships it is now usually the practice to connect the engines by means of a center shaft, 25 so that the power of both is applied to either wheel. In such cases it is best to connect the pistons appertaining to $c' c^2$ in the manner described, and for the reason that the two wheels are often when the ship is rolling 30 unequally immersed. In such cases one wheel immerses as the other emerges or nearly so and the steam applied to the engine should be graduated according to their mean dip. The connection shown effectually 35 answers this purpose, as the throttles are thereby moved according to the mean of the pressure on the small pistons. In a single engine ship this connection is also necessary, but in vessels where each engine 40 drives its own wheel the contrary is the case. This apparatus that is to say the pistons, cylinders, etc., with their attachments to the throttle may be applied advantageously to screw vessels, in which case the cylinder 45 should be located in the dead wood in the run, so that the pressure of the column of water on the outer side of the piston should

be proportional to the immersion of the screw propeller.

It is obvious that any train of motions 50 known to mechanics may be used for connecting the pistons with the throttles or for applying the force of weights or springs to thrust the pistons outward and that any known springs may be used for this purpose 55 or any known species of throttle valve be substituted for those shown in the drawings. It is further obvious that any known floats, valves, or connections may be used in place of those described in the condenser and channel way so long as the valves act as described when operated by the float. It is also clear that the equilibrium table may be used without the packing pieces $p p, p p$ and that the whole of the valve except a surface 60 equal to the area of the ports will then be balanced and also that the equilibrium table may be supported from the valve seat by legs of any kind instead of those represented or that it might be attached to the back of the 65 valve chest by means of rods passing through the slots $o o$ provided such slots were made as long as the travel of the valve.

Having thus described my invention and some of the modifications of which it is susceptible I claim as of my own invention— 75

1. The equilibrium table with its ledges or their equivalents applied to and acting in combination with the valve substantially as herein described. 80

2. I claim the packing pieces extending from the back of the valve chests and abutting against the back of the valve in combination with the small passages leading to the ports substantially in the manner herein described. 85

3. I claim combining the equilibrium table or its equivalent with the packing and small passages by the joint action of which a slide valve is perfectly and entirely balanced. 90

ROBERT WADDELL.
